UNITED STATES PATENT OFFICE.

JOSEPH TRIMBACH, OF RYE, NEW YORK.

NON-REFILLABLE BOTTLE.

1,095,607.

Specification of Letters Patent.

Patented May 5, 1914.

Application filed July 11, 1913. Serial No. 778,622.

To all whom it may concern:

Be it known that I, JOSEPH TRIMBACH, a citizen of the United States, residing at Rye, in the county of Westchester and State of New York, have invented certain new and useful Improvements in Non-Refillable Bottles; and I do hereby declare the following to be a full, clear, and exact description of the invention, such as will enable others skilled in the art to which it appertains to make and use the same.

This invention comprehends improvements in non-refillable bottles and has for its object the provision of a bottle having means contained within the neck thereof which will prevent the bottle being refilled after having been once emptied, said means being of extremely simple construction and very easy to assemble in its operative position.

The invention also aims to generally improve non-refillable bottles to render them more useful, practical, and commercially desirable.

With these and other objects in view, as will become more apparent as the description proceeds the invention consists in certain novel features of construction, combination, and arrangement of parts, as will be hereinafter described and claimed.

For a complete understanding of my invention, reference is to be had to the following description and accompanying drawings, in which,

Figure 1 is a fragmentary vertical sectional view through the neck of my improved bottle, Fig. 2 is a transverse section taken on the plane of line 2-2 of Fig. 1, Fig. 3 is a side elevation of the non-refillable means, and, Fig. 4 is a bottom plan view thereof.

In the preferred embodiment of my invention, I provide a bottle having a neck 5 which tapers gradually toward its inner end and which is enlarged adjacent said end to form an annular recess 6 and a shoulder 7. Within the neck is secured a substantially cylindrical valve cage casing or container, generally designated 8. This casing 45 extends the full length of the neck 5, is substantially cylindrical to conform to the interior of the neck, and is formed in two similar sections, designated by the numeral 9. The inner ends of the sections 9 are longitudinally slotted, as indicated by the numeral 10, to form spring fingers or jaws 11

of a somewhat segmental shape in cross section. These jaws are formed upon their exterior faces adjacent their lower ends with enlargements 12, which are adapted to 60 spring outwardly into the recess 6 under the shoulder 7 and lock the housing within the bottle neck. Since the neck tapers slightly toward its inner end, the housing cannot be forced inwardly beyond a certain predetermined distance. A preferably cork or 65 rubber sleeve 13 surrounds a portion of the sections 9 so as to prevent a leakage.

Each of the sections 9 is internally recessed so as to form, when the two sections 70 are brought together, a pocket to receive the valve cage. This cage is formed of an inner section, generally designated 14, and an outer section, generally designated 15. The inner section has a frusto-conical body 16 75 having a cylindrical neck or tube 17 formed upon its inner or smaller end. This tubular portion extends between the spring fingers or jaws 11 and has a rubber or cork sleeve 18 positioned between the jaws 11 and said 80 tubular portion. The sleeve surrounds the tubular portion 17 and bears against the jaws or fingers 11. A ball valve 19 is positioned within the frusto-conical body 16 and seats against the walls thereof when the 85 bottle is in a vertical position.

The outer portion 15 of the valve cage is of a tubular formation, having its inner end enlarged to a diameter corresponding with the opposed end of the body 16. This 90 enlarged inner end has formed integrally therewith a semispherical wall 20, provided with a plurality of apertures 21. The wall 20 prevents the ball 19 passing out of the cage when the bottle is inverted but permits 95 the liquid contents of the bottle to be discharged since the radius of the ball valve is smaller than the radius of the essentially semispherical wall 20.

To assemble the non-refillable means with 100 in a bottle neck 5, the ball 19 is first positioned within the body 16 and this body placed within one of the sections 9. The outer cage section 15 is then placed preferably within this section 9 and the co-operating section of the valve cage housing placed over the valve cage. Then the sleeve 13 is slipped over the two sections of the valve cage housing so as to hold them together and the sleeve 18 slipped over the tubular 110 section 17. The valve cage housing is then forced into the neck of the bottle. The

sleeve 18 being compressible, permits the spring fingers to be forced inwardly so that the valve cage casing may be easily forced into the neck 5 and when the housing or 5 casing is in its proper position, the spring fingers will spring outwardly so as to bring the enlargements 12 under the shoulder 7, thus preventing a removal of the housing.

It is to be understood that while I have 10 shown and described the preferred embodiment of my invention, I do not wish to be limited to this exact construction, combination, and arrangement of parts, but may make such changes as will fall within the 15 spirit and scope of the invention as claimed.

Having thus described my invention, I claim:—

A non-refillable bottle comprising a bottle with tapered neck, said neck provided 20 with a cutaway portion at its lower end forming a shoulder, a valve cage provided

with enlarged portions at its lower extremity and adapted to conform with the cut-away portion and the neck of said bottle, a frusto-conical body mounted in said cage 25 and formed in a pair of sections and adapted to receive a ball, said frusto-conical body provided with a tube at its lower end, one of the sections of the body portion being provided with an enlarged portion at its lower 30 extremity and adapted to register with the frusto-conical body, a dome-shaped cap secured to the lower extremity of the upper section of the body portion and provided with perforations therein and providing a 35 stop for the ball.

In testimony whereof I affix my signature in presence of two witnesses.

JOSEPH TRIMBACH.
